ACCESSORY TO TURNBUCKLE WRENCH

Thomas F. Hauck, Roscoe, Calif.

Application June 29, 1944, Serial No. 542,638

1 Claim. (Cl. 81—13)

1

This invention relates to new and useful improvements in tools and more particularly to a wrench accessory especially adapted for actuating turnbuckles.

The principal object of the present invention is to provide an accessory for a turnbuckle wrench constructed for facilitating the actuation of turnbuckles particularly on rigging aircraft cables.

Other objects and advantages of the invention will become apparent to the reader of the following description.

In the drawing:

Figure 1 represents a side elevational view of the wrench accessory.

Figure 2 is a top plan view of Figure 1.

Figure 3 is a longitudinal sectional view taken on the line 3—3 of Figure 2.

Figure 4 is an end elevational view of the wrench accessory.

Figure 5 is a cross-section taken on the line 5—5 of Figure 1.

Referring to the drawing wherein like numerals designate like parts, it can be seen that the wrench accessory consists of a pair of jaw arms 5, 6 having in continuation thereof jaw heads 7 with stepped-in openings 8 for accommodating the swaged ends of cables such as are used on rigging aircraft cables. At this point, let it be understood, that the wrench accessory is especially adapted to hold the swaged ends of a cable so as not to allow the cable to turn when the turnbuckle barrel is being rotated by the wrench proper. The stepped-in openings 8 in the jaw heads 7 serve to engage the swaged ends of the cable to hold the cable stationary while the turnbuckle is being so actuated.

The tool further consists of the tube 9 into which extends an elongated barrel 10. The tube 9 forms part of the arm 6 or is integrally formed or secured at right angles to said arm thereto, while the barrel 10 similarly carries the arm 5

2

at right angles. As is clearly shown in Figure 3, the barrel 10 is longitudinally slotted at 11 for receiving and guiding a pin 12 which extends through the tube 9 and into the barrel 10 through the slot 11.

An elongated tension spring 13 has one end anchored as at 14 to the arm 5 while its other end is secured to the pin 12, the spring extending longitudinally in the barrel 10 and is completely enclosed therein.

It can now be seen, that the tool can be expanded and the jaw head 7 placed over the swaged ends of cables connected to a turnbuckle (not shown) and thus the cables are held while the turnbuckle (not shown) is rotated by the wrench proper.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A wrench accessory for engaging the swaged ends of cables attached to a turnbuckle, comprising a pair of cable engageable jaws and a slideable connection transversely to and between said jaws, said connection consisting of a short tubular member integral with one jaw, and a long tubular member integral with the other jaw and telescopically mounted within said short member, a stud on the short member engaging a longitudinal slot provided in said long member, and tension means within said connection secured respectively at its opposite ends to said jaw members, whereby said jaws will accommodate themselves to hold the cables exteriorly to the ends of the turnbuckle.

THOMAS F. HAUCK.
